UNITED STATES PATENT OFFICE.

CLARENCE B. FOSTER, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

974,480.

Specification of Letters Patent.

Patented Nov. 1, 1910.

Application filed February 6, 1909. Serial No. 476,492.

To all whom it may concern:

Be it known that I, CLARENCE B. FOSTER, a citizen of the United States, residing at Detroit, in the county of Wayne and State of Michigan, have invented certain new and useful Improvements in Adding-Machines, of which the following is a specification.

The present invention relates to power-driven machines and as here shown and described is adapted to machines driven by an electric motor. The purpose is to prevent waste of power by the running of the motor when the machine is not being used. Means are provided for automatically turning off the current unless within a predetermined time after the current has been turned on, the machine is operated or unless operations of the machine continue. Thus if, after turning on the current or other source of power, the user should happen to be called away before operating the machine at all or if, after having operated the machine with the current turned on, he should neglect to turn off the current or should fail to do so from any cause, the current will be automatically turned off.

To this end the invention consists in certain novel features of construction and combinations of parts, the essential elements 30 whereof are recited in the appended claims and a preferred form of embodiment of which is described in detail hereinafter and fully illustrated in the accompanying drawings forming a part of this specification.

35 Of said drawings Figure 1 represents in right side elevation an electric drive for an adding machine, the present improvements being incorporated therein; Fig. 2 is a vertical cross-section taken on the line 2—2 of Fig. 1; Fig. 3 is an enlarged right side elevation of some of the parts shown in Fig. 1, together with a section of the switch with the latter represented as open; Fig. 4 is a view similar to Fig. 3 but representing the 40 switch as closed; Fig. 5 is a section taken at right angles to the section in Fig. 2 on line 5—5 of the latter; Fig. 6 shows the interior parts of the switch in elevation with the casing in section as well as the stem of the 45 switch button; Fig. 7 is a cross-section of the switch taken on the line 7—7 of Fig. 6; Fig. 8 is a horizontal section taken substantially on the line 8—8 of Fig. 3; and Fig. 9

is a detail cross-section taken on the line 9—9 of Fig. 8.

55

The invention is here shown and described as adapted to the form of electric drive for adding machines disclosed in Vincent Patent 866,750, issued September 24, 1907; see also Vincent Patent 894,550, issued July 28, 1908. In view of the disclosures in said 60 patents it will not be necessary in the present specification to particularize as to the construction of the motor and controlling devices therefor. Suffice it to state that the 65 numeral 2 (Fig. 2) designates a shaft carrying the driven member of a clutch and 3 a worm wheel carrying the driving member of the clutch which takes the form of a peripherally notched or corrugated ring 4 with 70 which is adapted to engage a dog 5 carried by a disk 6 secured to the shaft 2 and having a cylindrical portion 6^a surrounding said ring 4. An arm 5^a loose upon the hub of the disk 6 is geared to the dog 5 and a spring 5^b 75 applied to said arm tends to rock it in a direction to engage the dog with the corrugated ring 4 but normally the arm is restrained by a detent plug 5^c. The latter is 80 geared to an arm 5^d (Fig. 1) to which is coupled the lower end of a link 5^e operatively connected to a depressible starting bar 5^f. Depression of the latter closes the clutch in the manner explained in said 85 Vincent Patent 866,750, the detent plug 5^c being thereby disengaged from the arm 5^a. Said detent plug will be forcibly restored to effective position shortly after the machine starts to operate, by the action of an oscillatory member of the machine upon the 90 forward extension 5^g of said link 5^e, as also fully set forth in said Vincent patent.

The switch for turning on and off the current is of the familiar "snap" variety though modified considerably for the purposes of the present invention.

The numeral 8 designates the thumb piece or turn button of the switch which has a stem 9 (Fig. 7) extending through the cap 10 and the insulation base block 11. A coiled 100 spring 12 surrounds this stem, being secured at one end to a disk or collar 13 secured to the stem. The spring is contained within a sleeve 14 loosely surrounding the stem and the lower end of the spring is engaged 105 with said sleeve. There is secured to the

2
 lower end of the sleeve a disk 15 shouldered at diametrically opposite points as shown at 15^a and 15^b Figs. 3 and 4. There is also secured to said sleeve just above the disk 15 5 a plate 16 which carries spaced from it and with suitable intervening insulation the double-ended contact blade 17 adapted to coöperate with contact leaf springs 18 arranged in pairs as usual. The "off" positions of the blade 17 are determined by the alternate engagement of the shoulders 15^a and 15^b with a spring-pressed catch 19 pivoted to the base of the switch and having a cam tail 20 adapted to be acted upon alternately by cam projections 21 on a disk 22 secured to the stem 9 of the turn button. When the latter is turned with the catch 19 10 engaged with either of the shoulders 15^a or 15^b the spring 12 will necessarily be put under tension and then with continued 15 turning of the button and its stem one of the cam projections 21 will act upon the cam tail 20 of said catch, displace the latter and permit the spring to throw the blade into engagement with the contact springs 18. It 20 will be noted that a half rotation of the thumb piece is necessary in order to release the catch and thus sufficient power is stored in the spring to produce a half rotation of 25 the switch blade. However, the blade is restricted to a quarter rotation through means presently to be described, so as to hold the blade in the "on" position and reserve power of the spring to effect automatic opening of the switch. Thus a second 30 dog or catch 23 is pivoted on the base of the switch and spring-pressed against the disk 15 so as to alternately engage the shoulders 15^a and 15^b thereof, the engaging portion of 35 this second catch being a quarter turn distance from the engaging portion of the first-mentioned catch.

It will be obvious that with the above-described construction the turning of the 40 button a half rotation will result in release of the contact blade from the restraint of the dog or catch 19 and permit the spring 12 to give the blade a quarter turn, the shoulder disk 15 being then restrained by the second 45 dog or catch 23 as illustrated in Fig. 4. A spring-pressed pawl 24, pivoted on the base of the switch, engages the disk 22 and prevents retrograde movement of the switch button. Now the purpose is to control the 50 second dog or catch 23 by timing devices so that should the current be turned on but the machine not operated the contact blade will be automatically thrown to the "off" position after a predetermined lapse of time and 55 so that the same result will ensue a predetermined time after cessation of use of the adding machine. Thus there is pivoted to a supporting arm 25 on the switch base (Figs. 60 3 and 4) a bell crank lever 26 which carries 65 a spring-pressed flip pawl 27 adapted to

engage a cam projection 23^b on a depending arm 23^a of the catch or dog 23. The tail of the flip pawl underlies a lip 26^a on the lever 26 so that when such lever is rocked from the position shown in Fig. 4 the flip pawl 70 will displace said dog or catch.

As the apparatus stands normally the bell crank lever is in the position shown in Fig. 3 with the flip pawl above the cam projection. In being rocked from such position it does not affect the dog or catch, the flip pawl merely turning when engaged with the shoulder which terminates the cam projection 23^b and passing by the latter to the position shown in Fig. 4. The bell crank 75 lever 26 is connected by a link 28 with another bell crank lever 29 pivoted at 30 to the framework of the apparatus, one arm of said lever being connected by a comparatively strong spring 31 with a stud on such framework, said spring tending to swing rearwardly or to the right, as the parts are viewed in Figs. 3 and 4, the upstanding arm 80 of the lever. This latter arm at its upper end is pivotally connected to the head of a cylinder 32 which slides upon another cylinder 33, the latter being pivotally mounted at 34 to a suitably arranged bracket 35 on the framework of the apparatus. The head of the cylinder 33 is made with a series of 85 apertures 36 for intake of air, said apertures being covered on the interior of the cylinder by a leather disk or washer 37, (see Figs. 8 and 9.) An aperture 38 in the head of said cylinder registers with an aperture 39 in said leather disk or washer to provide for exhaust of air from the interior of the cylinders. A set screw 40 has a conical inner end to constitute a valve for regulating the exhaust. It will be obvious that 90 drawing forward of the upstanding arm of the lever 29 in opposition to the spring 31 will draw the cylinder 32 away from the cylinder 33 and suck air into the latter through the ports or apertures 36 as well as 95 the apertures 38 and 39. It will further be apparent that with the leather disk or washer 37 closing the ports 36 the exhaust of air will be confined to the restricted outlet 38 and hence return of the cylinder 33 100 will be retarded, to a great or less extent according to the adjustment of the valve 40. The idea is that when the current is turned on the lever 29 will be rocked to set this timing device above described and that if 105 the adding machine is not then operated within a predetermined length of time, that is to say, before the spring 31 moves said lever back to normal, the current will be turned off. This is obvious since the rocking of the lever against the stress of the spring 31 carries the flip pawl 27 down below the cam projection of the dog or catch 23 as illustrated in Fig. 4 and the return of the lever 29 causes the flip pawl to 110

displace the dog or catch. The means here shown for retracting or "priming" the lever 29 as the result of turning on the current, comprise a cam block or strip 41 (Figs. 5 3 and 8) secured to the side of the worm wheel 3 and a lever pivoted to the gear casing at 42, having a roller-equipped arm 43 for co-action with said cam and an arm 44 carrying a flip pawl 45 to operate a bell 10 crank lever 46 coupled by a link 47 with the lever 29. Now it will be understood of course that whenever the current is turned on the said worm wheel is in motion. Consequently very soon after the motor has 15 been started the lever arm 43 will be retracted by the action of the cam 41 against its roller. The normal condition of the parts is represented in Fig. 3, the flip pawl 44 being below the forwardly-extending arm 20 of the bell crank lever 46. When the said lever arm 43 is retracted by the cam the other arm 44 is rocked upwardly causing the flip pawl 45 to rock the bell crank lever 46 and through the link 47 retract the lever 25 29 to the position shown in Fig. 4. The pivot of the lever 43-44 is a short shaft 42 (Fig. 8) which carries an arm 48 connected by a spring 49 with the gear casing, such spring normally holding the lever to the 30 position shown in Fig. 3 with the flip pawl 45 below the forwardly-projecting arm of the bell crank lever 46 as shown in Fig. 3. The tail of the flip pawl 45 underlies a lip 44^a on the arm 44, being held thereagainst 35 by a spring 45^a from which it will be obvious that in upward rocking of the arm 44 the flip pawl will displace the bell crank 46. However, the relation of parts is such that as the lever 29 reaches the limit of its movement 40 under actuation of said flip pawl the arc described by the point of the latter will cross the arc described by the point of the forwardly-projecting arm of the bell crank 46, as indicated by dotted lines in Fig. 3, 45 with the result that these parts become disengaged and the lever 29 can return under actuation of its spring 31, independently of the lever 43-44.

In order to prevent re-setting or re-priming of the timing mechanism before the automatic opening of the switch can take place, the before-described lever 43-44 is latched in its displaced position and so held until the switch has opened. To this end the 50 arm 44 is prolonged and formed at its rear upper extremity with a laterally-turned lip 44^b which when said arm is rocked upward by the cam 41 rides over an inclined edge of an arm 50, the latter having a latching shoulder 50^a to engage under said lip when the latter passes and said arm being normally held toward a stop pin 51 by a coiled spring 52 connecting such stop pin with the arm. The bell crank lever 46 is secured to a 55 rock shaft 53 (Fig. 8) on which said arm 50

is loosely mounted and the arm has a lower extension 50^b which extends in rear of the coupling stud or pin 54 connecting the bell crank lever 46 and the link 47. Normally such coupling pin engages the arm as shown 70 in Fig. 3 holding it deflected against the stress of the spring 52 but as soon as the bell crank lever 46 has been rocked to a comparatively slight extent by the cam 41 the spring 52 will have drawn the upper portion 75 50 of the arm against the pin 51 and as the operation proceeds the lip 44^b will displace the arm in opposition to the spring 52 and bring about the latching of the lever 43-44 in the position to which it is moved by the 80 cam 41, as illustrated in Fig. 4. Near the close of the gradual return movement of the lever 29 and bell crank 46 the coupling pin 54 will strike the lower extension 50^b of the arm and displace it sufficiently to release the 85 lever 43-44 whose spring 49 then returns it to the position shown in Fig. 3, the switch having meantime been opened so that said lever will not be again retracted.

It is of course essential that the automatic 90 switch-opening mechanism shall not take effect if, following the turning on of the current, the adding machine is operated. Therefore means are provided for keeping the lever 29 retracted by the driven member 95 of the clutch. To this end a cam 60 (Figs. 2 and 5) is secured to the cylindrical portion 6^a of the clutch disk 6 and there is secured to the shaft 53 an arm 61 equipped with a roller to be acted upon by said cam 60. If, 100 within a reasonable time after turning on the current, the adding machine is operated, which means that the driving and driven members of the clutch are coupled together, then before the lever 29 will have had time 105 to move back under the impulse of its spring 31 far enough to open the switch, the cam 60 will act upon the arm 61 and rock the bell crank lever 46, thereby forcing the lever 29 forward in opposition to the spring 31. Of 110 course if operations of the adding machine continue with reasonable frequency repetitions of this effect will be produced. When such operations of the adding machine cease and are not resumed quite soon the dormant 115 state of the driven clutch member will permit the lever 29 to move gradually all the way back, causing the opening of the switch. It will be understood that the switch button having been turned half way around when 120 starting up the motor and the dog 27 limiting the resultant throw of the switch blade to a quarter turn, the switch spring 12 has not expended its force and that when the said dog 27 is thereafter tripped there is 125 sufficient reserve power in the spring to throw the switch blade another quarter turn.

While well adapted to fulfil the objects primarily stated, the particular construction here shown and described is of course sus- 130

ceptible of modification and the invention is not necessarily to be considered as limited in this regard.

What I claim is:

5. 1. The combination of the machine proper, a motor for driving the same, a clutch between the motor and the machine, means for starting and stopping the motor, and timing devices for operating said means to stop the 70 motor when the clutch is open.
10. 2. The combination of the machine proper, a motor for driving the same, a clutch between the motor and the machine, means for starting and stopping the motor, and motor- 75 set timing devices for operating said means to stop the motor when the clutch is open.
15. 3. The combination of the machine proper, a motor for driving the same, a clutch between the motor and the machine comprising 80 driving and driven members, means for starting and stopping the motor, and timing devices set by the driving member of the clutch and adapted to operate upon said means to stop the motor when the clutch re- mains open a predetermined length of time.
20. 4. The combination of the machine proper, a motor for driving the same, a clutch between the motor and the machine comprising driving and driven members, means for 85 starting and stopping the motor, timing devices adapted to operate upon said means to stop the motor when the clutch re- mains open a predetermined length of time, and means for keeping said timing devices set by the driven member of the clutch.
25. 5. The combination of the machine proper, an electric motor for driving the same, a clutch between the motor and the machine, a 90 switch for starting and stopping the motor, and timing devices for operating said switch to stop the motor when the clutch is open.
30. 6. The combination of the machine proper, an electric motor for driving the same, a clutch between the motor and the machine, a switch for starting and stopping the motor, and motor-set timing devices for operating said switch to stop the motor when the 95 clutch is open.
35. 7. The combination of the machine proper, an electric motor for driving the same, a clutch between the motor and the machine comprising driving and driven members, a switch for starting and stopping the motor, and timing devices set by the driving member of the clutch, and adapted to operate upon said switch to stop the motor when the clutch remains open a predetermined length of time.
40. 8. The combination of the machine proper, an electric motor for driving the same, a clutch between the motor and the machine comprising driving and driven members, a switch for starting and stopping the motor, and timing devices set by the driving member of the clutch, and adapted to operate upon said switch to stop the motor when the clutch remains open a predetermined length of time.
45. 9. The combination of the machine proper, a motor for driving the same, a clutch between the motor and the machine, means for starting and stopping the motor, and timing devices for operating said means to stop the motor when the clutch is open, said devices comprising a spring adapted to be put under tension by the motor and means for regulating the recovery of said spring.
50. 10. The combination of the machine proper, a motor for driving the same, a clutch between the motor and the machine comprising driving and driven members, means for starting and stopping the motor, and timing devices adapted to operate upon said means to stop the motor when the clutch remains open a predetermined length of time, said devices comprising a spring adapted to be put under tension by the driving member of the clutch together with means for regulating the recovery of said spring.
55. 11. The combination of the machine proper, a motor for driving the same, a clutch between the motor and the machine comprising driving and driven members, means for starting and stopping the motor, and timing devices adapted to operate upon said means to stop the motor when the clutch remains open a predetermined length of time, said devices comprising a spring adapted to be put under tension by the driving member of the clutch together with means for regulating the recovery of said spring; and means for keeping said spring under tension by the driven clutch member.
60. 12. The combination of the machine proper, an electric motor for driving the same, a clutch between the motor and the machine comprising driving and driven members, a switch for starting and stopping the motor, and timing devices adapted to operate upon said switch to stop the motor when the clutch remains open a predetermined length of time, said devices comprising a spring adapted to be put under tension by the driving member of the clutch together with means for regulating the recovery of said spring.
65. 13. The combination of the machine proper, an electric motor for driving the same, a clutch between the motor and the machine comprising driving and driven members, a switch for starting and stopping the motor, and timing devices adapted to operate upon said switch to stop the motor when the clutch remains open a predetermined length of time, said devices comprising a spring adapted to be put under tension by the driving member of the clutch together with means for regulating the recovery of said spring.

sion by the driving member of the clutch together with means for regulating the recovery of said spring; and means for keeping said spring under tension by the driven 5 clutch member.

14. The combination of the machine proper, an electric motor for driving the same, a clutch between the motor and the machine, a rotary circuit-closing member, a 10 spring adapted to be tensioned to turn said member, means for restraining the latter, means for releasing it as an incident to tensioning the spring to close the circuit, the tensioning of the spring being sufficient to 15 move the member on to break the circuit, means for checking the member in the closing position, and a timing device adapted to be set by the motor and to release the circuit-closing member from the closing position 20 when the motor has run a certain length of time with the clutch open.

15. The combination of the machine proper, an electric motor for driving the same, a clutch between the motor and the 25 machine, a rotary circuit-closing member, a spring adapted to be tensioned to turn said member, means for restraining the latter, means for releasing it as an incident to tensioning the spring to close the circuit, the 30 tensioning of the spring being sufficient to move the member on to break the circuit, means for checking the member in the closing position, and a timing device adapted to be set by the motor and to disable the 35 latter means.

16. The combination of the machine proper, an electric motor for driving the same, a clutch between the motor and the machine, a rotary circuit-closing member, a 40 spring adapted to be tensioned to turn said member, means for restraining the latter, means for releasing it as an incident to tensioning the spring to close the circuit, the tensioning of the spring being sufficient to 45 move the member on to break the circuit, means for checking the member in the closing position, and a spring-actuated timing device adapted to be set by the motor and to disable the latter means.

50 17. The combination of the machine proper, an electric motor for driving the same, a clutch between the motor and the machine comprising driving and driven elements, a rotary circuit-closing member, a 55 spring adapted to be tensioned to turn said member, means for restraining the latter, means for releasing it as an incident to tensioning the spring to close the circuit, the tensioning of the spring being sufficient to 60 move the member on to break the circuit, means for checking the member in the closing position, and a timing device adapted to be set by the driving member of the clutch and adapted to release the circuit-closing 65 member from the closing position when the

motor has run a certain length of time with the clutch open.

18. The combination of the machine proper, an electric motor for driving the same, a clutch between the motor and the 70 machine comprising driving and driven elements, a rotary circuit-closing member, a spring adapted to be tensioned to turn said member, means for restraining the latter, means for releasing it as an incident to tensioning the spring to close the circuit, the tensioning of the spring being sufficient to 75 move the member on to break the circuit, means for checking the member in the closing position, a timing device adapted to be set by the driving member of the clutch and adapted to release the circuit-closing member from the closing position when the motor has run a certain length of time with the clutch open, and means for maintaining the 80 85 said timing device set by the operation of the driven clutch member.

19. The combination of the machine proper, an electric motor for driving the same, a clutch between the motor and the 90 machine, a rotary circuit-closing member, a spring adapted to be tensioned to turn said member, means for restraining the latter, means for releasing it as an incident to tensioning the spring to close the circuit, the 95 tensioning of the spring being sufficient to move the member on to break the circuit, means for checking the member in the closing position, a trip for disabling said latter means, a lever connected to said trip, a 100 spring applied to said lever, means for retracting the lever by the motor in opposition to the spring, and means for retarding movement of the lever by the spring.

20. The combination of the machine 105 proper, an electric motor for driving the same, a clutch between the motor and the machine comprising driving and driven elements, a rotary circuit-closing member, a spring adapted to be tensioned to turn said 110 member, means for restraining the latter, means for releasing it as an incident to tensioning the spring to close the circuit, the tensioning of the spring being sufficient to move the member on to break the circuit, 115 means for checking the member in the closing position, a trip for disabling said latter means, a lever connected to said trip, a spring applied to said lever, means for retracting the lever by the driving member 120 of the clutch in opposition to the spring, means for retracting the lever by the driven member of the clutch, and means for retarding the advance of the lever by the spring.

21. The combination of the machine 125 proper, an electric motor for driving the same, a clutch between the motor and the machine, a rotary circuit-closing member, a spring adapted to be tensioned to turn said member, means for restraining the latter, 130

- means for releasing it as an incident to tensioning the spring to close the circuit, the tensioning of the spring being sufficient to move the member on to break the circuit, 5 means for checking the member in the closing position, a trip for disabling said latter means, a lever connected to said trip, a spring applied to said lever, means for retracting the lever by the motor in opposition to the spring, said means having pass-by provisions to provide for advance of the lever independently of the retracting means, and means for retarding movement of the lever by the spring. 10

15 22. The combination of the machine proper, an electric motor for driving the same, a clutch between the motor and the machine, a rotary circuit-closing member, a spring adapted to be tensioned to turn said member, means for restraining the latter, means for releasing it as an incident to tensioning the spring to close the circuit, the tensioning of the spring being sufficient to move the member on to break the circuit, 20 means for checking the member in the closing position, a trip for disabling said latter means, a lever connected to said trip, a spring applied to said lever, a cam on the driving member of the clutch, a lever operated by said cam and having a flip pawl, a lever operated by said flip pawl and connected to the first-mentioned lever, and means for retarding movement of the latter by its spring. 25

30 35 23. The combination of the machine proper, an electric motor for driving the same, a clutch between the motor and the machine, a rotary circuit-closing member, a spring adapted to be tensioned to turn said member, means for restraining the latter, means for releasing it as an incident to tensioning the spring to close the circuit, the tensioning of the spring being sufficient to move the member on to break the circuit, 35 means for checking the member in the closing position, a trip for disabling said latter means, a lever connected to said trip, a spring applied to said lever, a cam on the driving member of the clutch, a lever operated by said cam and having a flip pawl, a lever operated by said flip pawl and connected to the first-mentioned lever, a cam on the driven clutch member also adapted to operate said last-mentioned lever, and means for retarding movement of the first-mentioned lever by its spring. 40

proper, a motor for driving the same, a clutch between the motor and the machine, means for starting and stopping the motor, and fluid regulated timing devices for operating said means to stop the motor when the clutch is open.

28. The combination of the machine proper, a motor for driving the same, a clutch between the motor and the machine, 10 means for starting and stopping the motor, and fluid-regulated motor-set timing devices for operating said means to stop the motor when the clutch is open.

29. The combination of the machine proper, a motor for driving the same, a clutch between the motor and the machine comprising driving and driven members, means for starting and stopping the motor, and fluid regulated timing devices set by the 20 driving member of the clutch and adapted to operate upon said means to stop the motor when the clutch remains open a predetermined length of time.

30. The combination of the machine proper, a motor for driving the same, a clutch between the motor and the machine comprising driving and driven members, means for starting and stopping the motor, fluid regulated timing devices set by the 30 driving member of the clutch and adapted to operate upon said means to stop the motor when the clutch remains open a predetermined length of time, and means for keeping said timing devices set by the driven member of the clutch.

31. The combination of the machine proper, an electric motor for driving the same, a clutch between the motor and the machine, a switch for starting and stopping 40 the motor, and fluid regulated timing devices for operating said switch to stop the motor when the clutch is open.

32. The combination of the machine proper, an electric motor for driving the same, a clutch between the motor and the machine, a switch for starting and stopping the motor, and fluid-regulated motor-set timing devices for operating said switch to stop the motor when the clutch is open.

50 33. The combination of the machine proper, an electric motor for driving the same, a clutch between the motor and the machine comprising driving and driven members, a switch for starting and stopping 55 the motor, and fluid regulated timing devices set by the driving member of the clutch and adapted to operate upon said switch to stop the motor when the clutch remains open a predetermined length of time.

60 34. The combination of the machine proper, an electric motor for driving the same, a clutch between the motor and the machine comprising driving and driven members, a switch for starting and stopping 65 the motor, fluid regulated timing devices set

by the driving member of the clutch and adapted to operate upon said switch to stop the motor when the clutch remains open a predetermined length of time, and means for keeping said timing devices set by the 70 driven member of the clutch.

35. The combination of the machine proper, a motor for driving the same, a clutch between the motor and the machine, means for starting and stopping the motor, 75 and timing devices for operating said means to stop the motor when the clutch is open, said devices comprising a spring adapted to be put under tension by the motor and fluid regulated means for controlling the recovery 80 of said spring.

36. The combination of the machine proper, a motor for driving the same, a clutch between the motor and the machine comprising driving and driven members, 85 means for starting and stopping the motor, and timing devices adapted to operate upon said means to stop the motor when the clutch remains open a predetermined length of time, said devices comprising a spring 90 adapted to be put under tension by the driving member of the clutch together with fluid regulated means for controlling the recovery of said spring.

37. The combination of the machine proper, a motor for driving the same, a clutch between the motor and the machine comprising driving and driven members, means for starting and stopping the motor, and timing devices adapted to operate upon 100 said means to stop the motor when the clutch remains open a predetermined length of time, said devices comprising a spring adapted to be put under tension by the driving member of the clutch together with fluid 105 regulated means for controlling the recovery of said spring; and means for keeping said spring under tension by the driven clutch member.

38. The combination of the machine proper, an electric motor for driving the same, a clutch between the motor and the machine comprising driving and driven members, a switch for starting and stopping the motor, and timing devices adapted to 110 operate upon said switch to stop the motor when the clutch remains open a predetermined length of time, said devices comprising a spring adapted to be put under tension by the driving member of the clutch together 115 with fluid regulated means for controlling the recovery of said spring.

39. The combination of the machine proper, an electric motor for driving the same, a clutch between the motor and the machine comprising driving and driven members, a switch for starting and stopping the motor, and timing devices adapted to 125 operate upon said switch to stop the motor when the clutch remains open a predeter- 130

mined length of time, said devices comprising a spring adapted to be put under tension by the driving member of the clutch together with fluid regulated means for controlling 5 the recovery of said spring; and means for keeping said spring under tension by the driven clutch member.

40. The combination of the machine proper, an electric motor for driving the 10 same, a clutch between the motor and the machine, a rotary circuit-closing member, a spring adapted to be tensioned to turn said member, means for restraining the latter, means for releasing it as an incident to tensioning the spring to close the circuit, the 15 tensioning of the spring being sufficient to move the member on to break the circuit, means for checking the member in the closing position, and a fluid regulated timing 20 device adapted to be set by the motor and to release the circuit-closing member from the closing position when the motor has run a certain length of time with the clutch open.

41. The combination of the machine 25 proper, an electric motor for driving the same, a clutch between the motor and the machine, a rotary circuit-closing member, a spring adapted to be tensioned to turn said member, means for restraining the latter, 30 means for releasing it as an incident to tensioning the spring to close the circuit, the tensioning of the spring being sufficient to move the member on to break the circuit, means for checking the member in the closing 35 position, and a fluid regulated timing device adapted to be set by the motor and to disable the latter means.

42. The combination of the machine proper, an electric motor for driving the 40 same, a clutch between the motor and the machine, a rotary circuit-closing member, a spring adapted to be tensioned to turn said member, means for restraining the latter, means for releasing it as an incident to tensioning the spring to close the circuit, the 45 tensioning of the spring being sufficient to move the member on to break the circuit, means for checking the member in the closing position, and a spring-actuated fluid 50 regulated timing device adapted to be set by the motor and to disable the latter means.

43. The combination of the machine proper, an electric motor for driving the same, a clutch between the motor and the 55 machine comprising driving and driven elements, a rotary circuit-closing member, a spring adapted to be tensioned to turn said member, means for restraining the latter, means for releasing it as an incident to tensioning the spring to close the circuit, the 60 tensioning of the spring being sufficient to move the member on to break the circuit, means for checking the member in the closing position, and a fluid regulating timing device 65 adapted to be set by the driving member of

the clutch and adapted to release the circuit-closing member from the closing position when the motor has run a certain length of time with the clutch open.

44. The combination of the machine 70 proper, an electric motor for driving the same, a clutch between the motor and the machine comprising driving and driven elements, a rotary circuit-closing member, a spring adapted to be tensioned to turn said 75 member, means for restraining the latter, means for releasing it as an incident to tensioning the spring to close the circuit, the tensioning of the spring being sufficient to move the member on to break the circuit, 80 means for checking the member in the closing position, a fluid regulated timing device adapted to be set by the driving member of the clutch and adapted to release the circuit-closing member from the closing position 85 when the motor has run a certain length of time with the clutch open, and means for maintaining the said timing device set by the operation of the driven clutch member.

45. The combination of the machine 90 proper, an electric motor for driving the same, a clutch between the motor and the machine, a rotary circuit-closing member, a spring adapted to be tensioned to turn 95 said member, means for restraining the latter, means for releasing it as an incident to tensioning the spring to close the circuit, the tensioning of the spring being sufficient to move the member on to break the circuit, means for checking the member in the closing 100 position, a trip for disabling said latter means, a lever connected to said trip, a spring applied to said lever, means for retracting the lever by the motor in opposition to the spring, and fluid regulated means 105 for retarding movement of the lever by the spring.

46. The combination of the machine proper, an electric motor for driving the 110 same, a clutch between the motor and the machine comprising driving and driven elements, a rotary circuit-closing member, a spring adapted to be tensioned to turn said member, means for restraining the latter, 115 means for releasing it as an incident to tensioning the spring to close the circuit, the tensioning of the spring being sufficient to move the member on to break the circuit, means for checking the member in the closing 120 position, a trip for disabling said latter means, a lever connected to said trip, a spring applied to said lever, means for retracting the lever by the driving member of the clutch in opposition to the spring, means 125 for retracting the lever by the driven member of the clutch, and fluid regulated means for retarding movement of the lever by the spring.

47. The combination of the machine proper, an electric motor for driving the 130

- same, a clutch between the motor and the machine, a rotary circuit-closing member, a spring adapted to be tensioned to turn said member, means for restraining the latter, 5 means for releasing it as an incident to tensioning the spring to close the circuit, the tensioning of the spring being sufficient to move the member on to break the circuit, means for checking the member in the closing position, a trip for disabling said latter means, a lever connected to said trip, a spring applied to said lever, means for retracting the lever by the motor in opposition to the spring, said means having pass- 10 by provisions to provide for return movement of the lever independently of the retracting means, and fluid regulated means for retarding movement of the lever by the spring.
- 20 48. The combination of the machine proper, an electric motor for driving the same, a clutch between the motor and the machine, a rotary circuit-closing member, a spring adapted to be tensioned to turn said member, 25 means for restraining the latter, means for releasing it as an incident to tensioning the spring to close the circuit, the tensioning of the spring being sufficient to move the member on to break the circuit, means for check- 30 ing the member in the closing position, a trip for disabling said latter means, a lever connected to said trip, a spring applied to said lever, a cam on the driving member of the clutch, a lever operated by said cam and 35 having a flip pawl, a lever operated by said flip pawl and connected to the first-mentioned lever, and fluid regulated means for retarding movement of the latter by its spring.
- 40 49. The combination of the machine proper, an electric motor for driving the same, a clutch between the motor and the machine, a rotary circuit-closing member, a spring adapted to be tensioned to turn said member, 45 means for restraining the latter, means for releasing it as an incident to tensioning the spring to close the circuit, the tensioning of the spring being sufficient to move the member on to break the circuit, means for check- 50 ing the member in the closing position, a trip for disabling said latter means, a lever connected to said trip, a spring applied to said lever, a cam on the driving member of the clutch, a lever operated by said cam and 55 having a flip pawl, a latch for holding said latter lever in operated position, a lever operated by said flip pawl and connected to the first-mentioned lever, and fluid regulated means for retarding movement of the latter by its spring, said first-mentioned lever adapted to operate said latch at the close of 60 movement by its spring.
50. The combination of the machine proper, an electric motor for driving the same, a clutch between the motor and the machine 65 comprising driving and driven elements, a rotary circuit-closing member, a spring adapted to be tensioned to turn said member, means for restraining the latter, means for releasing it as an incident to tensioning the spring to close the circuit, the tensioning of the spring being sufficient to move the member on to break the circuit, means for checking the member in the closing position, a trip for disabling said latter means, 70 a lever connected to said trip, a spring applied to said lever, means for retracting the lever by the driving member of the clutch in opposition to the spring, said means having pass-by provisions to provide for advance of the lever independently of the retracting means, means for retracting the lever by the driven member of the clutch, and fluid regulated means for retarding the advance of the lever by the spring.
- 75 51. The combination of the machine proper, an electric motor for driving the same, a clutch between the motor and the machine comprising driving and driven elements, a rotary circuit-closing member, a spring 80 adapted to be tensioned to turn said member, means for restraining the latter, means for releasing it as an incident to tensioning the spring to close the circuit, the tensioning of the spring being sufficient to move the member on to break the circuit, means for checking the member in the closing position, a trip for disabling said latter means, a lever connected to said trip, a spring applied to said lever, a cam on the driving member of the clutch, a lever operated by said cam and 85 having a flip pawl, a lever operated by said flip pawl and connected to the first-mentioned lever, a cam on the driven clutch member also adapted to operate said last- 90 mentioned lever, and fluid regulated means for retarding movement of the first-mentioned lever by its spring.
- 95 52. The combination of the machine proper, an electric motor for driving the same, a clutch between the motor and the machine comprising driving and driven elements, a rotary circuit-closing member, a spring 100 adapted to be tensioned to turn said member, means for restraining the latter, means for releasing it as an incident to tensioning the spring to close the circuit, the tensioning of the spring being sufficient to move the member on to break the circuit, means for checking the member in the closing position, a trip for disabling said latter means, a lever connected to said trip, a spring applied to said lever, a cam on the driven clutch member also adapted to operate said last- 105 mentioned lever, and fluid regulated means for retarding movement of the first-mentioned lever by its spring.
- 110 53. The combination of the machine proper, an electric motor for driving the same, a clutch between the motor and the machine comprising driving and driven elements, a rotary circuit-closing member, a spring 115 adapted to be tensioned to turn said member, means for restraining the latter, means for releasing it as an incident to tensioning the spring to close the circuit, the tensioning of the spring being sufficient to move the member on to break the circuit, means for checking the member in the closing position, a trip for disabling said latter means, a lever connected to said trip, a spring applied to said lever, a cam on the driving member of the clutch, a lever operated by said cam and having a flip pawl, a latch for holding said latter lever in operated position, a lever operated by said flip pawl and connected to the first-mentioned lever, a cam on the driven clutch member also adapted to operate said last- 120 mentioned lever, and fluid regulated means for retarding movement of the first-mentioned lever by its spring.
- 125 54. The combination of the machine proper, an electric motor for driving the same, a clutch between the motor and the machine comprising driving and driven elements, a rotary circuit-closing member, a spring 130 adapted to be tensioned to turn said member, means for restraining the latter, means for releasing it as an incident to tensioning the spring to close the circuit, the tensioning of the spring being sufficient to move the member on to break the circuit, means for checking the member in the closing position, a trip for disabling said latter means, a lever connected to said trip, a spring applied to said lever, a cam on the driven clutch member also adapted to operate said last-mentioned lever, and fluid regulated means for retarding movement of the first-mentioned lever by its spring.

lever, and fluid-regulated means for retarding movement of the first-mentioned lever by its spring, said first-mentioned lever adapted to operate said latch at the close of 5 movement by its spring.

53. The combination of the machine proper, a motor for driving the same, a clutch between the motor and the machine comprising driving and driven members, 10 means for starting and stopping the motor, and timing devices adapted to operate upon said means to stop the motor when the clutch remains open a predetermined length of time, said devices comprising a spring adapted 15 to be put under tension by the driving member of the clutch together with telescoped cylinders ported and valved for fluid intake and restricted exhaust.

54. The combination of the machine proper, an electric motor for driving the same, a clutch between the motor and the machine, a rotary circuit-closing member, a spring adapted to be tensioned to turn said member, means for restraining the latter, 20 means for releasing it as an incident to tensioning the spring to close the circuit, the tensioning of the spring being sufficient to move the member on to break the circuit, means for checking the member in the closing position, a trip for disabling said latter means, a lever connected to said trip, a spring applied to said lever, means for retracting the lever by the motor in opposition to the spring, and means for retarding movement of the lever by the spring, said means 25 comprising telescoped cylinders ported and valved for fluid intake and restricted exhaust.

55. The combination of the machine proper, an electric motor for driving the same, a clutch between the motor and the machine, a rotary circuit-closing member carrying a shouldered disk, a rotary manipulating member carrying a cam disk, a spring 40 connecting the said two members, a pawl to engage the shouldered disk and adapted to be displaced by the cam disk, a second pawl to engage said shouldered disk, and timing means for displacing said second pawl.

56. The combination of the machine proper, an electric motor for driving the same, a clutch between the motor and the machine, a rotary circuit-closing member carrying a shouldered disk, a rotary manipulating member carrying a cam disk, a spring 45 connecting the said two members, a pawl to engage the shouldered disk and adapted to be displaced by the cam disk, a second pawl to engage said shouldered disk, and a lever 50 having a flip pawl to displace said second pawl, and timing means connected to said lever.

57. The combination of the machine proper, a motor for driving the same, a

clutch between the motor and the machine, 65 means for starting and stopping the motor, and timing devices for operating said means to stop the motor when the clutch is open, said devices comprising a spring-held lever adapted to be retracted by the motor and 70 means for regulating return movement of said lever.

58. The combination of the machine proper, a motor for driving the same, a clutch between the motor and the machine 75 comprising driving and driven members, means for starting and stopping the motor, and timing devices adapted to operate upon said means to stop the motor when the clutch remains open a predetermined length of 80 time, said devices comprising a spring-held lever adapted to be retracted by the driving member of the clutch, and means for regulating the return movement of said lever.

59. The combination of the machine 85 proper, a motor for driving the same, a clutch between the motor and the machine comprising driving and driven members, means for starting and stopping the motor, timing devices adapted to operate upon said 90 means to stop the motor when the clutch remains open a predetermined length of time, said devices comprising a spring-held lever adapted to be retracted by the driving member of the clutch, and means for regulating the return movement of said lever; and means for keeping the latter retracted 95 by the driven member of the clutch.

60. The combination of the machine proper, an electric motor for driving the same, a clutch between the motor and the machine comprising driving and driven members, a switch for starting and stopping the motor, and timing devices adapted to operate upon said switch to stop the motor 100 when the clutch remains open a predetermined length of time, said devices comprising a spring-held lever adapted to be retracted by the driving member of the clutch, and means for regulating the return movement of 105 said lever.

61. The combination of the machine proper, an electric motor for driving the same, a clutch between the motor and the machine comprising driving and driven members, a switch for starting and stopping the motor, timing devices adapted to operate upon said switch to stop the motor when the clutch remains open a predetermined length of time, said devices comprising a 110 spring-held lever adapted to be retracted by the driving member of the clutch, and means for regulating the return movement of said lever; and means for keeping the latter retracted by the driven member of the clutch. 115

62. The combination of the machine proper, a motor for driving the same, a clutch between the motor and the machine,

means for starting and stopping the motor, and timing devices for operating said means to stop the motor when the clutch is open, said devices comprising a spring-held lever

5 adapted to be retracted by the motor and telescoped cylinders ported and valved for fluid intake and restricted exhaust, one of said cylinders being connected to said lever.

63. The combination of the machine proper, a motor for driving the same, a clutch between the motor and the machine comprising driving and driven members, means for starting and stopping the motor, and timing devices adapted to operate upon 10 said means to stop the motor when the clutch remains open a predetermined length of time, said devices comprising a spring-held lever adapted to be retracted by the driving member of the clutch, and telescoped cylinders ported and valved for fluid intake and 15 restricted exhaust, one of said cylinders being connected to said lever.

64. The combination of the machine proper, a motor for driving the same, a clutch between the motor and the machine comprising driving and driven members, means for starting and stopping the motor, timing devices adapted to operate upon 20 said means to stop the motor when the clutch remains open a predetermined length of time, said devices comprising a spring-held lever adapted to be retracted by the driving member of the clutch, and telescoped cylinders ported and valved for fluid intake and 25 restricted exhaust, one of said cylinders being connected to said lever.

65. The combination of the machine proper, an electric motor for driving the same, a clutch between the motor and the machine comprising driving and driven members, a switch for starting and stopping the motor, and timing devices adapted to 30 operate upon said switch to stop the motor when the clutch remains open a predetermined length of time, said devices comprising a spring-held lever adapted to be retracted by the driving member of the clutch, and telescoped cylinders ported and valved for fluid intake and 35 restricted exhaust, one of said cylinders being connected to said lever; and means for keeping the latter retracted by the driven member of the clutch.

66. The combination of the machine proper, an electric motor for driving the same, a clutch between the motor and the machine comprising driving and driven members, a switch for starting and stopping the motor, timing devices adapted to operate upon 40 said switch to stop the motor when the clutch remains open a predetermined length of time, said devices comprising a spring-held lever adapted to be retracted by the driving member of the clutch, and telescoped cylinders ported and valved for fluid intake and 45 restricted exhaust, one of said cylinders being connected to said lever; and means for keeping the latter retracted by the driven member of the clutch.

67. The combination of the machine proper, an electric motor for driving the same, a clutch between the motor and the machine comprising driving and driven members, a switch for starting and stopping the motor, timing devices adapted to operate upon 50 said switch to stop the motor when the clutch remains open a predetermined length of time, said devices comprising a spring-held lever adapted to be retracted by the driving member of the clutch, and telescoped cylinders ported and valved for fluid 55 intake and restricted exhaust, one of said cylinders being connected to said lever; and means for keeping the latter retracted by the driven member of the clutch.

68. The combination of the machine proper, a motor for driving the same, a clutch between the motor and the machine, means for starting and stopping the motor, and timing devices for operating said means to stop the motor when the clutch is open, 60 said devices comprising a spring-held lever, means for retracting the same by the motor with pass-by provisions for permitting independent return movement of the lever, and means for regulating such return move- 65

70 ment. 75

68. The combination of the machine proper, a motor for driving the same, a clutch between the motor and the machine comprising driving and driven members, 80 means for starting and stopping the motor, and timing devices adapted to operate upon said means to stop the motor when the clutch remains open a predetermined length of time, said devices comprising a spring-held lever, means for retracting the same by the driving member of the clutch with pass-by provisions for permitting independent return movement of the lever, and means for regulating such return movement. 85

69. The combination of the machine proper, a motor for driving the same, a clutch between the motor and the machine comprising driving and driven members, means for starting and stopping the motor, 90 timing devices adapted to operate upon said means to stop the motor when the clutch remains open a predetermined length of time, said devices comprising a spring-held lever, means for retracting the same by the driving member of the clutch with pass-by provisions for permitting independent return movement of the lever, and means for regulating such return movement. 95

70. The combination of the machine proper, an electric motor for driving the same, a clutch between the motor and the machine comprising driving and driven 100 members, a switch for starting and stopping the motor, and timing devices adapted to operate upon said switch to stop the motor when the clutch remains open a predetermined length of time, said devices comprising a spring-held lever, means for retracting the same by the driving member of the clutch with pass-by provisions for permitting independent return movement of the lever, and means for regulating such return movement; and means for keeping the latter retracted by the 105 driven member of the clutch. 110

71. The combination of the machine proper, an electric motor for driving the same, a clutch between the motor and the machine comprising driving and driven members, a switch for starting and stopping the motor, 115 timing devices adapted to operate upon said switch to stop the motor when the clutch remains open a predetermined length of time, said devices comprising a spring-held lever, means for retracting the same by the driving member of the clutch with pass-by provisions for permitting independent return movement of the lever, and means for regulating such return movement. 120

71. The combination of the machine proper, an electric motor for driving the same, a clutch between the motor and the machine comprising driving and driven members, a switch for starting and stopping 125

130

the motor, timing devices adapted to operate upon said switch to stop the motor when the clutch remains open a predetermined length of time, said devices comprising a 5 spring-held lever, means for retracting the same by the driving member of the clutch with pass-by provisions for permitting independent return movement of the lever, and means for regulating such return movement; 10 and means for keeping the latter retracted by the driven member of the clutch.

72. The combination of the machine proper, a motor for driving the same, a clutch between the motor and the machine 15 comprising driving and driven members, means for starting and stopping the motor, and timing devices adapted to operate upon said means to stop the motor when the clutch remains open a predetermined length of 20 time, said devices comprising a cam on the driving member of the clutch, a spring-held lever adapted to be retracted by said cam and carrying a flip pawl, a second lever adapted to be operated by said flip pawl, a 25 spring-held lever adapted to be retracted by said second lever, and means for regulating

the return movement of said last-mentioned spring-held lever.

73. The combination of the machine proper, a motor for driving the same, a 30 clutch between the motor and the machine comprising driving and driven members, means for starting and stopping the motor, and timing devices adapted to operate upon said means to stop the motor when the clutch 35 remains open a predetermined length of time, said devices comprising a cam on the driving member of the clutch, a spring-held lever adapted to be retracted by said cam and carrying a flip pawl, a second lever 40 adapted to be operated by said flip pawl, a spring-held lever adapted to be retracted by said second lever, means for regulating the return movement of said last-mentioned spring-held lever, and a latch for holding the 45 first spring-held lever displaced, said latch adapted to be displaced by the other spring-held lever in return movement thereof.
